OTTO PETERMANN, OF GROTON, NEW YORK, ASSIGNOR TO CORONA TYPEWRITER COMPANY, INCORPORATED, A CORPORATION OF NEW YORK.

TYPE-WRITING MACHINE.

1,215,699.

Specification of Letters Patent. Patented Feb. 13, 1917.

Application filed August 26, 1913. Serial No. 786,693.

To all whom it may concern:

Be it known that I, OTTO PETERMANN, a citizen of the Republic of Switzerland, and a resident of Groton, county of Tompkins, 5 and State of New York, have invented certain new and useful Improvements in Type-Writing Machines, of which the following is a full, clear, and exact description.

This invention relates more particularly 10 to the line-lock mechanism and means for stopping the carriage.

One of the principal objects of the invention is to provide simple and efficient means whereby the carriage may be fed for letter 15 spacing in the usual way and at the end of the line positively locked against movement and such locking mechanism released and the carriage again fed one or more spaces for the purpose of adding an additional letter or letters at the end of a line and then again positively locked against further movement.

Another object of the invention is to provide a line-lock mechanism which comprises 20 but few parts and in which a single element forms a direct lock between the carriage and a part of the mechanism actuated as the keys are depressed.

A further object of the invention is to provide a simple and efficient device which is 25 movable with the carriage and which operates the line-lock lever.

A still further object of the invention is to provide simple and efficient means mounted 30 on the carriage and which may be utilized as positive stops to lock the carriage in its movement in either direction.

With these and other objects in view, the 35 invention will be hereinafter more particularly described with reference to the accompanying drawings, which form a part of this specification, and will then be pointed out in the claims at the end of the description.

In the drawings, Figure 1 is a longitudinal section of one form of typewriting machine showing one embodiment of my invention applied thereto.

Fig. 2 is a rear elevation of the carriage and carriage bed removed from the rest of 50 the machine.

Fig. 3 is a detail plan view of the carriage bed showing a part of the key-actuated mechanism and the line-lock lever, the means for actuating the lever being shown in section.

Fig. 4 is a side elevation of the carriage. Fig. 5 is a plan view of the member or device for moving the line-lock lever.

Fig. 6 is a detail perspective view of the line-lock lever engaging member or device, 60 showing how the same may be adjustably held to a bar mounted on the carriage; and

Fig. 7 is a detail perspective view of a slightly different form of device or engaging member.

While the invention is shown more particularly as applied to a type of machine in which the carriage and platen is folded forward into overhanging relation to the keyboard as in the Corona typewriting machine, 70 it will be understood that the invention may be applied to typewriting machines of various kinds.

The frame 10 may have sides 10^a, a cross-bar or part 11 at the front of the machine 75 and a bar or plate 12 at the rear thereof which serve to connect the sides 10^a together and which may be separate from or integral therewith. A number of key-operated levers 13 are suspended from a support 14 and said levers are each normally forced 80 in one direction by a spring 15, the latter being secured at one end to the key-lever at a point beyond the pivot 14 and to a transverse plate 16 secured to the machine frame. The 85 key-levers at their inner ends have a lug 17 which is connected by a link 18 to a type-bar 19. Each type-bar 19 is pivotally held to a hanger 20 suitably supported by the rear frame plate 12, and each type-bar is adapted 90 to lie against a rest 21. The type-bars are each provided with a type-block having a plurality of characters thereon and which is adapted to be forced as each key-lever is depressed against the work sheet on the platen 95 22. The platen 22 is mounted upon the carriage 23 which is adapted to travel back and forth on the carriage bed 24, there being suitable letter-spacing mechanism provided to feed the carriage in one direction. This 100 carriage bed is rigidly held to the arms or bars 25 of a foldable support so as to adapt the carriage and bed to be folded forward into overhanging relation to the keys in position to be supported by the upper edge of 105 the machine frame 10.

A universal bar 26 is located above the key-levers as well as the spacing levers, and said universal bar is adapted to be engaged by a tongue or projection 27 of each key- 110

lever. The universal bar is provided with upwardly extending arms 28 and these arms are pivotally connected to the arms 29 of bell-crank levers 30, there being a bell-crank lever and a universal bar arm 28 at each side of the machine. Each bell-crank lever is pivoted at 31 and has one arm, as 32, extending vertically and said arms 32 are connected together by a transversely extending rod 33. This rod 33 passes through slots 34 of upright rocking arms 35. The arms 35 are pivotally held to the transverse rod 36 at the lower part of the machine frame and at the upper end said arms are connected by the integral bar 37. This bar or member 37 has a tappet or part 38 which is adapted to engage the dog carrier indicated at 38^a or other part of an escapement mechanism in order that the carriage may be moved by its propelling means for letter spacing. It will be evident that as each key-lever 13 is depressed, one of the type-bars 19 will be moved by its link 18 and at the same time the tongue 27 of each key-lever will engage the universal bar so as to rock the bell-cranks 30 on their pivots. As the bell-crank levers are rocked, the rod 33 will rock the arms 35 and consequently move the bar 37 and cause the tappet 38 to engage the dog carrier and thereby permit the carriage to move a single space. The arms 35 and the bar 37 form a universal bar or rocking frame and said frame as well as the other parts thus far described, may be of the usual or of any preferred construction.

A lever 39 is pivoted at 40 to the under face of the bed 24 and is normally forced against a stop 41 by a spring 42. The forward end of the lever 39 is bent downward, as at 43, and is adapted to be moved into the path of a tappet or projection 44 carried by the transverse bar 37 of the rocking frame. When the lever 39 is moved into the path of the projection 44 as will be herein-after described, the bar 37 as well as the entire rocking frame will be prevented from being moved by the writing or spacing levers and consequently the said levers cannot be depressed.

To move the lever 39 on its pivot as the carriage is forced along its bed, a device 45 is provided. This device is mounted upon a bar 46 which is pivotally held to the carriage frame at the rear of the platen 22. The bar 46 is normally forced in one direction by a spring 47 to force the device 45 into position to engage a part of the lever 39 as the carriage moves along its bed and approaches the end of a line. The bar 46 has one end projecting through one end of the carriage frame and held to said bar is a lever 48. The lever 48 has an extension 49 with one end bent inward to engage one edge of the carriage frame and at its other end 65 extends forward and is provided with a fin-

ger piece or key 50. As the key 50 is depressed, the lever 48 will tilt the bar 46 and will thereby move the device 45 away from the outer end of the lever 39 to permit further movement of the carriage after it has once been locked. The device 45 has a pendent arm 51 and this arm is adapted to engage either of the fingers or projections 52 or 53 of the lever 39, the said fingers being spaced apart any suitable distance so that the pendent arm 51 will first engage the projection 52 and after being released will engage on further movement of the carriage the projection or finger 53. It will thus be evident that as the carriage moves along its bed, the pendent arm 51 by engagement with the projection 52 will force the end 43 of the lever 39 into the path of movement of the projection 44 of the rocking or universal bar frame and thus lock said frame and the key-levers 13 against movement. By operating the lever 48 to move the bar 46 on its pivot, the device 45 may be moved out of the path of the projection 52 of the lever 39 and the spring 42 will then shift the lever to the position shown in Fig. 3. The key-levers may again be depressed so that the carriage may be moved a further distance in the usual way and until the pendent arm 51 engages the finger or projection 53. When this takes place, the end 43 is again moved into the path of the projection 44 of the universal bar frame, thus again locking said frame and key-levers against movement. It will be seen, therefore, that one or more characters 100 may be added to the end of the line if desired and the carriage locked against further movement.

The member or device 45 may be variously constructed. As shown it comprises two members 54 and 55. The locking member 54 is provided with a head 56 and the guiding member 55 with a head 57. These members are made of flat sheet metal formed by dies or otherwise and the heads 56 and 57 are substantially U-shaped in plan and one head fits within the other in such a way as to permit relative movement. The head 57 may be called the guiding head for the device and the head 56 the locking head. The bar 46 has a plurality of vertically extending slots 57^a spaced apart and adapted to engage said slots is a dog or tooth 58 of the head 56. The guiding head 57 is provided with openings through the side plates or walls 59 of substantially the same size and shape as the bar 46 in order that it may be properly guided along the bar 46, and the head 55 has an opening longer than the bar 46 on the side or wall 60 only. The side 61 of the head 56 is relatively shorter than the side 60 and permits said head 56 to span the head 57 so as to be guided properly thereby. The head 56 has a pendent part or arm 62 which is secured to the pendent part or arm 130

51 by a screw 63 or otherwise. A flat spring 64 is interposed between the arms or parts 51 and 62 and extends upward between the heads 56 and 57 and normally forces one of the heads along the other and normally causes the dog or tooth 58 to engage one of the slots of the bar 46 and be held to said bar 46 in one of its adjustments. The head 56 is roughened to provide a finger surface 65 so that by pressing with the finger on the head 56, the tooth 58 may be disengaged from one of the slots 57 and the entire device moved along the bar 46, and on releasing the head 56 of any pressure by the finger, the device will be locked to the bar in any desired position. In this way the carriage may be locked at various points by simply adjusting the device 45.

A device 66 is located at the opposite end 20 of the bar 46 and is similarly constructed to the device 45. A third device 66^a is arranged on the bar 46 intermediate the devices 45 and 66, and said device 66^a is adjustable on said bar and is located on the same side of the machine as the device 66. The device 66^a is similarly constructed to the other devices except that the pendent arm or part 51 is not so long as in the devices 45 and 66 and may be only of a length corresponding to the arm or part 62. The stop 66^a acts as a regular stop for a plain margin and stop 66 is a special additional margin stop which might be adjusted to any suitable distance from the stop 66^a.

35 It will be evident that if the carriage is moved backward in the usual way until the stop 66^a engages the projection 67 on the bracket 68 the usual degree of margin may be secured. If, however, the bar 47 is moved 40 by operating the finger lever 48, the stop 66^a may be released from the projection 67 and the carriage given a further backward movement until the arm 51 of the device 66 engages the stop or projection 67. If an additional margin is desired, the device 66 may be released from the projection 67 and the carriage moved still farther backward until the arm 51 of the device 66 engages the projection or finger 53 of the lever 39 which 45 forms a stop for the arm 51. If the carriage is moved the latter distance, that is, until the arm 51 of the device 66 engages the finger 53 of the lever 39, the machine may be operated in the usual way for letter writing 50 and as the carriage moves toward the left or forward, the arm 51 of the device 66 will engage the projection 67, but owing to it being rounded on one edge, as at 69, the said arm will pass by said projection 67 and the writing 55 may continue for the reason that the bar 46 being rotatable, it will be automatically moved by said arm 51 of the device 66. As thus constructed, the left hand margin on the work sheet may be given one of several 60 adjustments for the writing of notes, etc., or

only one adjustment may be used or none whatever according to whether or not the device 66^a is employed or both devices. It will be understood that either of the stops 66 or 66^a may be dispensed with and that instead of rounding the part 67, the arm 51 of the device 66 may be twisted to form a cam surface or the said arm 51 may be twisted and the projection 67 also rounded as preferred.

70 The rocking frame as a ready explained operates a part of the letter spacing mechanism and is also adapted to operate other parts of a typewriting machine, as the ribbon mechanism for example. The letter 80 spacing and ribbon mechanisms do not form a necessary part of the present invention and further illustration or description thereof is considered unnecessary, as these or other parts operated by the rocking frame or 85 other key-actuated members may be of any suitable or preferred construction.

75 The construction of device shown in Fig. 7 is exactly the same as the device 45 except that the spring 64 is dispensed with. 90 In such case the member 54 or the pendent part 62 may be of spring metal to permit relative movement of the members 54 and 55. A spiral spring instead of a flat spring may be used, and either kind of spring may 95 be employed with a spring part 62 if desired.

80 From the foregoing, it will be seen that a simple and efficient line-lock mechanism is provided whereby the carriage may be 100 locked at a plurality of points to adapt a character or characters to be added at the end of a line; that said mechanism may be applied to typewriting machines and the like of various constructions; that a simple and efficient adjustable device or stop is provided to coöperate with and form a part of the line-lock mechanism; that said mechanism forms substantially a direct connection between the key-operated mechanism 105 and the carriage; and that a simple and efficient means is provided for writing marginal notes or for other purposes.

85 Having thus described my invention, I claim as new and desire to secure by Letters Patent:—

90 1. In a typewriting machine, the combination of a support, a carriage adapted to travel along said support, a key-actuated member, a bar having a relative rocking movement only mounted on said carriage, a device adjustably held to said bar and pendent therefrom, a lever pivotally held to the support and having one end provided with two spaced engaging parts arranged in the path of movement of said device and having its other end adapted to be moved into the path of movement of said key-actuated member and adapted to directly engage said member and hold the same against 120

125 130

movement when either of said engaging parts are engaged by said device, and means for releasing the device from engagement with the key-actuated member whereby said member may be held against movement at two distinct points.

2. In a typewriting machine, the combination of a support, a carriage adapted to travel along said support, a key-actuated 10 rocking frame, a horizontally arranged bar having a rocking movement and mounted on said carriage, a device held to said bar and pendent therefrom, a horizontally arranged lever pivotally held to the support and having one end provided with a plurality of engaging parts arranged in the path of movement of said device and having its other end adapted to be moved into the path of movement of said rocking frame and adapted 15 to directly engage said frame and hold the same against movement when said engaging parts are engaged by said device, and means for releasing the device from engagement with the lever.

25 3. In a typewriting machine, the combination of a support, a carriage adapted to travel along said support, a key-actuated member, a bar having a rocking movement and mounted on said carriage, a device held 30 to said bar and pendent therefrom, a lever pivotally held to the support under the same and having one end provided with spaced engaging parts arranged in the path of movement of said device and having its 35 other end adapted to be moved into the path of movement of the key-actuated member and adapted to engage directly said member and hold the same against movement when said engaging parts are engaged 40 by said device, and a finger lever for rocking the bar and releasing the device from engagement with the key-actuated member to hold the same against movement at distinct points.

45 4. In a typewriting machine, the combination of a movable carriage, a support therefor; a platen supported on the carriage, a rocking frame, key-operated levers for moving said frame, a horizontally arranged and pivotally held locking lever located under the support and adapted to move 50 into the path of a part of the rocking frame and prevent the same from moving, a spring normally forcing the locking lever in one direction, said lever having two spaced projecting portions, and a pendent and rocking device movable with the carriage and adapted 55 to engage the projecting portions of the lever in succession and to be released therefrom to permit movement of the frame and then automatically lock the frame again against movement.

60 5. In a typewriting machine, the combination with a support, of a carriage adapted to move along the support, a bar supported

by the carriage and having a rocking movement only thereon, a device carried by the bar, a rocking bar having a projection, a lever provided with two projecting parts spaced apart and adapted to be engaged by the device mounted on said bar and having its other end provided with a downwardly extending end adapted to engage the projection on the movable bar to lock the same against movement, and a spring for 75 forcing the lever out of engagement with said projection.

6. In a typewriting machine, the combination with a support, of a carriage adapted to move along the support, a bar supported by the carriage, a device carried by the bar, a rocking frame, key-operated levers connected to rock said frame, a lever provided with two projecting parts spaced apart and adapted to be engaged by the device in succession and having its other end provided with a part adapted to engage with a part of the rocking frame to lock the same against movement, and a spring for forcing the lever out of engagement with said frame. 90

7. In a typewriting machine, the combination of a support, a carriage adapted to travel along said support, a key-actuated member, a bar having a relative rocking movement only mounted on the carriage, devices adjustably held to said bar and pendent therefrom, a normally fixed bracket having a part adapted to be engaged by one of said devices to limit the movement of the carriage in one direction, a lever pivotally held to the support and having one end provided with two spaced engaging parts arranged in the path of movement of said devices and having its other end adapted to be moved into the path of movement of said key-actuated member and adapted to engage directly said member and hold the same against movement when either of said parts of the lever are engaged by one of said devices, said lever being adapted to be engaged 100 by the other of said devices during the movement of the carriage in its backward movement, and means for releasing the devices from engagement with the lever. 110

8. In a typewriting machine, the combination of a support, a carriage adapted to travel along said support, a key-actuated rocking frame, a bar having a relative rocking movement only mounted on the carriage, devices adjustably held to said bar and pendent therefrom, a normally fixed bracket having a part adapted to be engaged by one of said devices to limit the movement of the carriage in one direction and to move the device and bar when the carriage moves in 120 the opposite direction, a lever pivotally held under the support and having one end provided with two spaced engaging parts arranged in the path of movement of one of said devices and having its other end adapt- 125 130

ed to be moved into the path of movement of said key-actuated frame and hold the same against movement when either of said parts of the lever are engaged by one of said devices, said lever being adapted to be engaged by the other of said devices during the movement of the carriage in its backward movement, and means for releasing the devices from engagement with the lever.

10 9. In a typewriting machine, the combination of a support, a carriage adapted to travel along said support, a key-actuated frame, a bar having a rocking movement mounted on the carriage, devices adjustably held to said bar, and a lever pivotally held to the support and having one end provided

with spaced engaging parts arranged in the path of movement of one of said devices and having its other end adapted to be moved into the path of movement of said key-actuated frame when engaged by one of said devices, said lever being adapted to be engaged by the other of said devices during the movement of the carriage in its backward movement.

25 This specification signed and witnessed this 19th day of August, A. D. 1913.
